UNITED STATES PATENT OFFICE.

JAMES M. ARNOLD, OF CHICAGO, ILLINOIS.

LUBRICATOR FOR ELEVATORS.

SPECIFICATION forming part of Letters Patent No. 398,685, dated February 26, 1889.

Application filed November 16, 1888. Serial No. 290,984. (No model.)

To all whom it may concern:

Be it known that I, JAMES M. ARNOLD, a citizen of the United States, residing at Chicago, in the county of Cook and State of Illinois, have invented certain new and useful Improvements in Lubricators for Elevators, of which the following is a specification, to wit:

My invention relates to an improvement in lubricator for elevators; and it consists in 10 certain peculiarities of the construction and arrangement of the same, substantially as will be hereinafter more fully set forth and claimed.

In order to enable others skilled in the art to 15 which my invention pertains to make and use the same, I will now proceed to describe its construction and operation, referring to the accompanying drawings, in which—

Figure 1 is a perspective view of my invention ready for use. Fig. 2 is a sectional view of Fig. 1, and Fig. 3 is a modification.

Similar letters of reference refer to similar parts throughout the several views.

The object I have in view is to provide a 25 cup or receptacle containing a lubricant so arranged that it will automatically lubricate the guides of an elevator at all times and avoid the necessity of stopping the elevator and lubricating, as is usual now in such cases.

30 A represents the well-known guides in elevators, made in the well-known way, and b the supporting cross-beam at the top of the elevator-carriage.

C is the iron frame or slide, which is on the 35 ends of the supporting cross-beam of the elevator-carriage, these parts being so well-known and common in all elevators as to need no more description in detail.

On top of the beam b, I fix an arm or bracket, d, to sustain a cup or receptacle, e, this cup being made of any form or style, except that it is bifurcated to overlap or straddle the elevator-guide. This cup e is inclosed at top and bottom on its outer surface, so as to form a re-

45 ceptacle for the lubricating compound, and is provided with a suitable opening, f, through which the lubricating compound is exposed and is pressed against the elevator-guide. The cup e is formed with extensions g, which rest 50 in slotted supports h of the bracket d, and is secured in position by bolts, screws, or other-

wise. On the inside of the cup e, I provide a loose plate, j, behind the lubricating compound, and through the casing extends a screw, k, which screws against the plate j, so 55 that when the lubricant becomes worn by contact with the guide by simply screwing the screw k the plate j presses the lubricant forward, so as to be in contact with the guide A. On the arm or bracket d, I hang a weighted 60 lever, l, which presses against the cup e, as clearly shown in the drawings. This lever, continually pressing against the cup e, keeps it in close proximity with the guides A and compensates for the oscillating movement of 65 the carriage which occurs in the operation of the elevator.

While I have shown a weighted lever, which I prefer to use, yet sometimes I substitute a spring, which in like manner presses against 70 the cup and keeps it in position, and serves the same purpose as the lever.

On the top of the cup e, I show a feed, m, through which the lubricant is fed to the cup. While I have shown the cup separate from 75 the slide C, I intend in some cases to make the slide C and cup e in one piece, as shown in Fig. 3, in which case I may provide openings f in the cup, and a similar plate with screw and weighted lever adjustment, where- 80 by the lubricant may be forced forward to be kept continually in contact with the guide. I find by experience that I prefer to use as a lubricant a mixture of asbestos and oil, but it is evident that any lubricant not productive 85 of combustion can be used, such as soap, cotton-seed, &c. No matter what lubricant I use I shall so arrange it that the lubricant will be pressed forward against the guide, so that the elevator-guides will at all times be automatically lubricated when operated, and dispense with the necessity of the elevator being stopped at times for the operator to lubricate it, or for some one to ride on the cross-beam to perform the same purpose. 90

The operation of the device is simple and evident. The compound for lubricant having been placed in position in the cup and the elevator operated, the lubricant will be continually forced against the guide and will automatically and at all times thoroughly lubricate the guides. Any number of the cups 95 100

may be used as may be necessary, and may be made of any suitable material.

Having fully described my invention, what I claim as new, and desire to secure by Letters Patent, is—

1. In a lubricator for elevators, a bifurcated cup for containing a lubricant, in combination with the guides and carriage of an elevator, whereby the guides are automatically lubricated, substantially as shown and described, and for the purpose set forth.

2. In a lubricator for elevators, a bifurcated cup for containing a lubricant fixed on a bracket attached to the cross-beam of elevator-carriage, in combination with a weighted lever, and the elevator-guide, substantially as shown and described, and for the purpose set forth.

3. In a lubricator for elevators, the combination of the cup *e*, having the openings *f*, 20 the guide *A*, a suitable bracket, *d*, whereon said cup is movably mounted, and a lever, *l*, for forcing the cup normally toward the guide, substantially as described.

4. In a lubricator for elevators, the combination, with the cup *e*, having the openings *f*, 25 the adjustable plate *j*, and extensions *g*, of the guide *A*, a suitable bracket, *d*, having slotted supports *h*, and a lever, *l*, all constructed and arranged for operation substantially as described.

JAMES M. ARNOLD.
